UNITED STATES PATENT OFFICE.

HENRY W. COVERT, OF NEW YORK, N. Y., ASSIGNOR TO MARVIN'S SAFE COMPANY, OF SAME PLACE.

IMPROVEMENT IN TUMBLERS FOR PERMUTATION-LOCKS.

Specification forming part of Letters Patent No. 151,277, dated May 26, 1874; application filed January 10, 1874.

To all whom it may concern:

Be it known that I, HENRY W. COVERT, of the city, county, and State of New York, have invented a new and useful Improvement in Combination-Locks, of which the following is a specification:

The invention will first be fully described, and then pointed out in claim.

In the accompanying drawing, Figure 1 is a view of the rear side of the lock with the rear plate removed. Fig. 2 is a cross-section of Fig. 1, taken on the line *x x*. Fig. 3 is a side view of one of the combination-wheels, showing the slots for the movable pin and the open slot for releasing the bolt. Fig. 4 is a cross-section of Fig. 3, taken on the line *y y*.

Similar letters of reference indicate corresponding parts.

The general operation of this lock is similar to the combination-locks now in use—that is, having a spindle, dial, and driving-wheel, with one or more revolving combination-wheels.

A is the dial-plate. B is the spindle. C is the driving-wheel, made fast to the spindle. D represents the door to which the lock is attached. E is the back plate of the lock, which has a socket-center, F, around which the combination-wheels are revolved. G represents the reversible combination-wheels—one or more of which may be used—which are made to revolve around the socket-center F by turning the driving-wheel C, and are each numbered to indicate the combination. H represents slots in these wheels G, more or less in number, according to the number of changes which it is desired to make. These wheels have figures or numbers upon each of their sides, so that they may be reversed as may be required. I is the changeable pin, having a stem, J, and two jaws, K, with an open slot between the jaws, which receives the rim L of the wheel. The stem J fits into and fills the lower portion of the slot in the wheel, and the jaws K K project on each side of the wheel, as seen in Fig. 4, so that when one of these pins is placed in any one of the slots H of the combination-wheels the first wheel will be revolved by the stationary pin N in the driving-wheel, which pin will strike one of the

jaws. The opposite jaw of this pin in the first wheel will strike the pin in the next wheel, and revolve that, and so on for any number of wheels. This pin I may be changed to any of the slots H, and the combination is altered by such change.

By making these pins with jaws projecting on each side of the combination-wheels, those wheels may be reversed, and by making the pins changeable the number of combinations is greatly increased.

These pins I are held in position by the open slot between the jaws K K, which receives the rim of the wheel, and by loose washers O at their inner ends, which keep the stem J flush with the sides of the wheels.

By removing the washers O, or one of them, the wheels, or one of them, are readily taken from the center F and reversed, or one or more of the pins are changed, as may be desired.

By changing the pin from one slot to another, as already described, the number of combinations is greatly increased, and the lock is rendered far more intricate than it otherwise would be.

By reversing the wheels the combinations are greatly increased; but by changing the driving-pins, with numbers arranged between the slots, as represented, the power of the lock is increased according to the number of slots in the wheel or changes of the pin.

Wheels for combination-locks have been made in two parts, in one of which is the slot for releasing the bolt, and in the other the pin for turning the wheels, and having numbers to indicate the combinations whenever the relative positions of the pin and slot are changed.

Wheels for combination-locks have also been made of a single piece, and having a pin in each side, so as to make them interchangeable and reversible.

The outer row of numbers indicates the combination when used for the first wheel on the post, the second row for the second wheel, and the inner row for the third wheel.

The wheels are numbered in such a way that the combination may be read or known in whatever position the wheels are placed on

the post without resorting to other means to determine it.

Having thus described my invention, I claim as new and desire to secure by Letters Patent—

The combination, with movable pin and numbered wheels, of jaws K K, having open

slot, between them, and washers O, all constructed and arranged substantially as and for the purpose specified.

HENRY W. COVERT.
